US00D629921S

(12) **United States Design Patent**
Southwell

(10) **Patent No.:** **US D629,921 S**
(45) **Date of Patent:** ** *Dec. 28, 2010

(54) **BUILDING ELEMENT**

(75) Inventor: **Darren Southwell**, Bella Vista (AU)

AU 90831 8/1985

(73) Assignee: **James Hardie Technology Limited**,
Dublin (IE)

(Continued)

(**) Term: **14 Years**

(21) Appl. No.: **29/351,069**

Scyon™ Matrix™ website printed Sep. 13, 2006 at <http://www.jameshardie.com.au/Products/Scyon/Cladding/Matrix/default.htm>.

(22) Filed: **Nov. 30, 2009**

DESCRIPTION

FIG. 1 is a first perspective view of a building element;
FIG. 2 is a first end view of the building element shown in FIG. 1;
FIG. 3 is a first side view of the building element shown in FIG. 1;
FIG. 4 is a plan view of the building element shown in FIG. 1;
FIG. 5 is a second side view of the building element shown in FIG. 1;
FIG. 6 is a second end view of the building element shown in FIG. 1;
FIG. 7 is a bottom view of the building element shown in FIG. 1; and,
FIG. 8 is a second perspective view of a building element shown in FIG. 1.
